UNITED STATES PATENT OFFICE.

ELIZABETH G. TEBBUTT, OF ALBANY, NEW YORK.

BOTTLE.

SPECIFICATION forming part of Letters Patent No. 582,380, dated May 11, 1897.

Application filed February 26, 1897. Serial No. 625,205. (No model.)

To all whom it may concern:

Be it known that I, ELIZABETH G. TEBBUTT, a citizen of the United States, residing at Albany, in the county of Albany and State 5 of New York, have invented new and useful Improvements in Bottles, of which the following is a specification.

My invention relates to bottles having one or more quantum-measures connected with 10 an end thereof and provided with passage-ways communicating between said measures and the chamber of the bottle, and having each a discharge-opening which is pendent and below the plane of said passage-ways 15 when the liquid is to be drawn therefrom; and the objects of my invention are to provide, with a bottle, quantum-measures, one or more, each of arbitrary capacity and below an intake communicating with the chamber of the 20 bottle and having a stoppered pendent discharge; to provide a bottle with quantum-measures having each a pendent discharge-opening, one or more, in situation below the plane of the intake passage-way when the 25 bottle is in position for discharge; to provide a duplex chambered bottle with quantum-measures each connected with a different chamber thereof and provided with an intake-passage and a pendent discharge-opening, 30 adapted to be closed at will by a stopper, and, finally, to provide specific means by which my invention may be embodied in bottles. I attain these objects by means illustrated in the accompanying drawings, in which—

35 Figure 1 is a longitudinal section of a bottle embodying my invention. Fig. 2 is a view of the same from above. Fig. 3 is a longitudinal section of a duplex chambered bottle embodying my invention. Fig. 4 is a view 40 from above of the same, and Fig. 5 is a section taken at line I in Fig. 3.

The same letters of reference refer to similar parts throughout the several views.

In Figs. 1 and 2, A is the body of a bottle. 45 A' is the chamber thereof. a is the neck, and a' is a cork or stopper closing the mouth of the latter. This bottle may be of any preferred form and be of glass or other suitable substance and with any preferred capacity 50 for holding liquids.

B are quantum-measures, shown to be of different sizes and having their walls b inte-

gral (or connected) with the walls of the neck a and their chambers connected each with the throat of said neck by an intake port or 55 opening b'. The quantum measuring-chambers B' of these measures are shown to be on a plane below dotted line x, Fig. 1, drawn horizontal at the lower side of said intake-port b' when the bottle is in position shown. 60 A discharge-opening B² (shown to be pendent) is provided at the lower side of each said measure and closed by a suitable stopper b², which is removable at will.

In Figs. 3 and 4 a duplex bottle is shown, 65 in which bottle are embodied two separate chambers A' A', each separated from the other by one or more division-walls a². Figs. 3 and 4 also show the usual neck of the bottle to be dispensed with and liquid-filling mouths 70 C C, Fig. 4, to be provided and through which liquids may be introduced within the respective chambers A' A' of the bottle. Corks c c are shown closing said mouths. The quanta B B in this duplex bottle are shown to have 75 their respective intake ports or openings b' communicating each with a different bottle-chamber A' and having their respective measuring-chambers B' on a plane below the lower sides of their respective intake- 80 openings b' when the bottle is in position to allow a discharge of liquid from said quantum-measures through their respective discharge-openings B² when the stoppers b² are removed. If preferred, the filling-mouths C C 85 may be omitted from this duplex bottle, and the filling of each chamber thereof may be made through the respective discharge-openings B² when the bottle is in suitable position therefor. This duplex bottle when made of 90 glass may be made in halves in suitable molds and have their flat sides brought together or near each other, when their edge margins d d will be fused together or cemented to each other or be otherwise secured together. If 95 preferred, the quantum-measure ends of this bottle, whether single or duplex, may be made flat to adapt said ends to serve as the bottom end of the bottle, from which it may stand upright. These quantum-measures may have 100 made with their side walls subquantum measure-lines, as e e', serving to mark measures of less quantity than the whole of a quantum-measure B when the bottle stands upright by

so inclining the bottle that said lines e or e' will be relatively horizontal and coincident with horizontal dotted line x , when the liquid above said lines e or e' may run back into the bottle and leave in the quantum-measure the submeasure designed to be taken from the bottle.

By my above-described improvements the necessity of using an instrument apart from the bottle is obviated, and varying quantities for adults, youths, and children may readily be taken from the same bottle and introduced into a drinking-glass or other vessel in a cleanly manner and without recourse to the use of spoons or graduating-glasses.

Having described my invention, what I claim, and desire to secure by Letters Patent, is—

1. A bottle having a quantum-measure located wholly below an intake communicating with the chamber of the bottle and having a discharge-opening which is on a plane below the said intake, substantially as and for the purposes set forth.
2. A bottle having a quantum-measure located below an intake communicating with the chamber of the bottle and having one or more submeasure-marks arranged on an incline in relation to a horizontal line drawn at the lower side of said intake, and from the latter toward a discharge-opening located below the plane of said intake substantially as and for the purposes set forth.
3. A bottle having one or more quantum-measures each of capacity different from that of the other, and provided each with an intake which communicates with the chamber of the bottle and is above a discharge-opening adapted to be opened or closed at will,

substantially as and for the purposes set forth.

4. A bottle having a quantum-measure located below an intake communicating with the chamber of the bottle and provided with a discharge-opening which is at a plane below said intake when the quantum-measure contains only its selected measured quantity and ready to be discharged, substantially as and for the purposes set forth.

5. A bottle adapted to be inverted at will and having a quantum-measure connected with its body and provided with an intake communicating with the chamber of the bottle and having also a discharge-opening which will be below the plane of the bottom of said intake when said quantum-measure is at the upper end of the bottle substantially as and for the purposes set forth.

6. A bottle adapted to be inverted at will and having a quantum-measure connected with its body and provided with an intake communicating with the chamber of the bottle and having also a discharge-opening adapted to be closed at will, and located above the plane of the intake of the quantum-measure, when the latter is at the lower end of the bottle and before being inverted so as to be at the upper end substantially as and for the purposes set forth.

7. A duplex bottle having separated chambers and a quantum-measure having its chamber communicating with a different chamber of the bottle, as and for the purposes set forth.

ELIZABETH G. TEBBUTT.
